UNITED STATES PATENT OFFICE

PARIS R. FORMAN, OF RAHWAY, NEW JERSEY, ASSIGNOR TO NATIONAL PNEUMATIC COMPANY, OF NEW YORK, N. Y., A CORPORATION OF WEST VIRGINIA

ELECTRIC TREADLE

Application filed September 15, 1931. Serial No. 562,989.

This invention relates to improvements in electric treadles such as those used in connection with power operated doors on vehicles, buses and the like.

5 One of the objects of this invention is the provision of a unitary electric treadle structure which may be mounted in place in front of a door as a unit.

10 A further object of this invention is to provide a simplified electric treadle structure comprising a unitary supporting frame with the various parts thereof mounted entirely upon the unitary frame.

15 A further object of this invention is the provision of a structure of this nature which is relatively simple, relatively cheap to manufacture and of a rugged construction.

These and many other objects as will appear from the following disclosure are secured by means of this invention.

This invention resides substantially in the combination, construction, arrangement and relative location of parts all as will be described in detail hereinafter.

25 Referring to the drawings—

Fig. 1 is a top plan view of the treadle of this invention;

Fig. 2 is a cross-sectional view taken on the line 2—2 of Fig. 1;

30 Fig. 3 is a cross-sectional view taken on the line 3—3 of Fig. 1.

It is present practice to provide various forms of transportation vehicles such as street cars, buses and the like, with power operated doors. It is common to provide 35 some form of treadle control mounted in the floor adjacent the door so that when the treadle is depressed other preparatory conditions having occurred the door will open automatically. The general purpose of this invention is to provide an improved and simplified unitary treadle construction for such uses. It is hardly necessary to point out that the invention is not limited in use to vehicles

40 since it can be used in connection with the doors of buildings and like structures where, upon the depression of the treadle, the door will be automatically opened.

45 Referring to the drawings the treadle is shown comprising a U-shaped frame 1 closed

at its open end by means of an angle bar 2. At 3 is a movable treadle plate which is secured to and within the frame by means of a suitable hinge 4. The treadle plate is provided at all of its edges with depending 55 flanges 4' secured to the under surface of the treadle plate. On the side flanges are two bearing members 5 in which the transverse shaft 6 is journaled. Secured to this shaft near its end is a short lever arm 9 which is 60 provided at its outer end with a roller 8. The frame 1 is of a construction indicated in Figs. 1 and 2 and comprises two parallel flange members extending in opposite directions from a central vertical uniting strip. 65 The rollers 8 rest upon the flanges 1'. Secured to the under surface of the treadle is a switch casing 9 from which extends the insulated electric cable 10 provided with a suitable coupling device 11. The switch arm 70 (not shown) within the casing 9 is operated by means of a push button 12 which projects from the casing. At this point it is noted that the details of the switch structure are not given because any suitable form of 75 switch structure may be employed.

Secured near the center of shaft 6 is a lever arm 13 which lies under the push button 12 as is clear from Fig. 3. This lever arm is provided with an extension 14 which engages 80 with the under surface of the treadle plate. A threaded pin 19 extends through the treadle plate and the lever arm 14 and is provided with a thumb nut 20. A compression spring 21 lies between this thumb nut and 85 the arm 14 so as to normally urge the arm into the position shown in Fig. 3 and out of engagement with push button 12. The frame 1 is provided with a struck-up stop arm 15 provided with a resilient contact pad 90 18 for the engagement with arm 17 secured to the under surface of the treadle by means of a bracket 16.

As shown in Figs. 2 and 3 the treadle is normally in slightly raised position with respect to its frame when there is no weight thereon. This position of the treadle is maintained by means of the spring 12 which causes the composite arm or lever 13, 14 to assume the position shown in Fig. 3. This causes 100

shaft 6 to raise in such a position that arms 7 are moved to a position so that the rollers 8 thereon engage with the flanges 1' and hold the treadle in raised position. The engagement of arm 17 with stop arm 15 limits the upper movement of the treadle plate. When a person steps on the treadle plate it is depressed and as a result shaft 6 and arm 18 are rotated so that arm 13 moves towards and 10 against push button 12 to move it into the casing 9 to close the switch. In accordance with practice in this art this switch is included in suitable control circuits so that the power device for operating the door causes 15 the door to open. If the circuits are otherwise set for door opening operation when the treadle is relieved of pressure it returns to normal raised position under the pressure exerted by spring 21 acting through shaft 20 6 and the arms 7.

From the above description it will be apparent that this invention resides in certain principles of construction and operation which may be carried out in other physical 25 forms and I do not, therefore, desire to be strictly limited to the disclosure as given for purposes of illustration but rather to the scope of the appended claims.

What I seek to secure by United States 30 Letters Patent is:

1. A treadle construction comprising a supporting frame, a treadle plate hingedly secured in said frame, a shaft journalled on said treadle plate, arms secured to said shaft, and spring means operating with said shaft to cause said arms to engage the frame to hold the treadle plate in raised position.

2. A treadle construction comprising a supporting frame, a treadle plate hingedly secured in said frame, a shaft journalled on said treadle plate, arms secured to said shaft, spring means operating with said shaft to cause said arms to engage the frame to hold the treadle plate in raised position, and stop 45 means for limiting the movement of the treadle under the action of said spring means.

3. A treadle construction of the type described, comprising a frame, a treadle plate pivotally secured in said frame, a switch secured to the treadle plate, a shaft journalled on said treadle plate and having arms secured thereto in a position to engage said frame, a lever secured to said shaft, and spring means acting through said lever, shaft and arms to hold the treadle plate in raised position.

4. A treadle construction of the type described, comprising a frame, a treadle plate pivotally secured in said frame, a switch secured to the treadle plate, a shaft journalled on said treadle plate and having arms secured thereto in a position to engage said frame, a lever secured to said shaft, spring means acting through said lever shaft and 65 arms to hold the treadle plate in raised posi-

tion, said lever being positioned to operate said switch when the treadle is depressed.

5. A treadle construction of the type described, comprising a frame, a treadle plate pivotally secured in said frame, a switch attached to the under surface of said treadle plate for movement therewith, and spring pressed arms secured to said treadle plate for resiliently resisting its movement and for operating said switch when pressure is applied to the treadle plate.

In testimony whereof I have hereunto set my hand on this 20th day of August, A. D. 1931.
